William Reijo Williamson

UNITED STATES PATENT OFFICE

EINAR PEARSON, OF MINNEAPOLIS, MINNESOTA

BRUSH-HOLDING RECEPTACLE

Application filed May 15, 1926. Serial No. 109,405.

This invention relates to a brush holding device, and while the invention is capable of many different applications, it particularly is designed for holding brushes in a liquid containing receptacle. As is well known to those skilled in the art, it is desirable to keep paint brushes soft and pliable between periods of usage, and it is often desired to hold the brushes with the bristle portion disposed in suitable liquids.

It is an object of this invention, therefore, to provide a very simple and efficient brush holding means adapted to hold a plurality of brushes, the same being constructed and arranged so that anyone of the brush holding means may be readily removed and replaced.

It is a further object of the invention to provide a brush holding device adapted to be supported in or on a liquid holding receptacle, which device comprises a frame having a plurality of brush holding means disposed along one side thereof, together with removable means for holding said brush holding means in place.

It is more specifically an object of the invention to provide a receptacle, an open-work frame conforming in shape to the receptacle and supported therein, said frame having a plurality of brush holding clips carried thereon and removable clamping means holding said clips in position.

These and other objects and advantages of the invention will be fully set forth in the following description made in connection with the accompanying drawings, in which like reference characters refer to similar parts throughout the several views and in which:

Fig. 1 is a plan view of the device;

Fig. 2 is a vertical section taken on line 2-2 of Fig. 1;

Fig. 3 is a vertical section taken on line 3-3 of Fig. 1;

Fig. 4 is a vertical section taken on line 4-4 of Fig. 1; and

Fig. 5 is a vertical section taken on line 5-5 of Fig. 1, said sections being taken on said lines as indicated by the arrows.

Referring to the drawings, a receptacle 7

is shown, and while this receptacle may be of any desired shape, in the embodiment of the invention illustrated it is shown as rectangular in form. Said receptacle has lugs or ears 7b secured centrally at its ends, to which is pivoted the bail handle 16. Handle 16 has the revoluble grip member 16a at the center thereof. Said receptacle has a partition 7a extending transversely thereof at one side of its center, thus forming two compartments in the receptacle. The brush holding means comprises a frame 8, which frame is shown as formed from a simple, flat bar bent into shape fitting snugly within the walls of the receptacle 7. Said frame has hook clips 9 thereon adjacent one corner having upper portions adapted to overlap the top edge of the receptacle for holding said frame in place. Said frame also has secured to the bottom portion thereof adjacent one longitudinal side, a bar 10 which preferably will be spot-welded to the bottom edges of the ends of the frame 8, said bar thus leaving a narrow slot 10a between its edge and the adjacent side of the frame 8. A plurality of brush holding clips 11 are provided and while these clips might be variously formed, in the embodiment of the invention illustrated they are shown as substantially U-shaped in plan, having a central straight portion 11c and arms 11b bent to project substantially at right angles to the end of portions 11a, which arms converge toward each other and are then reversely curved as shown at 11e to form an oblong receiving portion, the ends of the arms 11b diverging at their terminal portions. The clips 11 rest upon the bar 10 and are clamped in position by a removable strip or bar 12 extending across the top of the frame 8 substantially over the bar 10, the ends of the strip 12 also extending over the edges of receptacle 7 and are turned downwardly a short distance. The bar 12 has secured thereto the spaced members 13 formed from simple flat material bent substantially at right angles, having top portions riveted or spot-welded to the top of bar 12 and the other portions extending vertically between the portions 11a of the clips

11 and the bar 10. The bars 10 and 12 and the end members 13 are supported to have passed therethrough the headed bolts 14 adapted to receive the clamping wing nuts 15 at their upper ends which seat on the members 13. The clips 11 are thus clamped between the bars 10 and 12 by tightening of the bolts 14. A bolt 17 has its head secured in the side of the frame 8 adjacent bar 10 and projects forwardly through a U-shaped clip 19 extending between the bars 10 and 12 and fitting over the same. The bolt 17 is threaded to receive the clamping wing nut 18 so that bar 12 can be moved toward the side of the receptacle 8 and the members 13 tightly clamped against the portions 11a of clips 11 so that said clips are thus clamped between the members 13 and the side of the frame 8.

20 In operation, a liquid indicated as 20 will be placed in the compartments of the container 7, which may be water or other liquid, for the purpose of keeping the brushes soft. The brushes 21 will be disposed with their bristle portions in the liquid 20 and in vertical position with their handle portions 21a pushed into and held by the clips 11 between the portions 11c thereof, as indicated in dotted lines in Fig. 2. The receptacle 7 can thus be carried by its handle and the brushes will be properly held in position therein. It is desirable to have the two compartments so that paint brushes may be disposed in one, and varnish brushes in another. The frame 8 can be lifted from the receptacle as a unit, with or without the brushes therein and as stated; said frame is held in said receptacle and at the top thereof by the clips 9 and the ends of the bar 12. 40 By loosening the nut 15 and lifting the bar 12 with its attached members 13, any one of the clips 11 can be removed. If a clip becomes broken, therefore, it is an easy matter to replace the same with a new one. The 45 clips are quite simple in construction and easily made and placed in position. The frame 8 and bar 12 as well as the clips can also thus be easily disassembled for cleaning. The device is adapted to hold any size brush as it is unnecessary to have any holes in the brush handle. It will also be noted that there are no holes in the clips 11 for holding them in position. Where such spring clips have apertures therein for holding means such as bolts, the clips are weakened so that they frequently break.

From the above description it will be seen that applicant has provided an extremely simple and efficient construction of brush holding device. The parts are few, simple in construction and easily made and assembled. The device has been amply demonstrated in actual practice and found to be very successful and efficient.

65 It will, of course, be understood that vari-

ous changes may be made in the form, details, arrangement and proportions of the parts, without departing from the scope of applicant's invention, which, generally stated, consists in a device capable of carrying out the objects above set forth, in the novel parts and combinations of parts disclosed and defined in the appended claims.

What is claimed is:—

1. A brush holding device having in combination, a rectangular open-work frame, a bar secured to the bottom of said frame and extending between the ends thereof adjacent one side, a U-shaped spring clip having a straight central portion extending along and in engagement with said side of said frame and having pairs of opposed spring arms extending substantially at right angles at each end thereof, a bar extending across the top of said frame and having spaced means extending downward therefrom at the side of the central portion of said clip opposite said side of said frame and means for moving and holding said last mentioned bar with the means thereon towards said side of said frame.

2. A holding means for a plurality of brush holding clips comprising a rectangular frame adapted to fit in the top of a receptacle, means on said frame engaging over the sides of said receptacle to support said frame therein, a bar extending across the bottom of said frame and secured thereto adjacent one side thereof, a bar extending across the top of said frame, a member carried by one of said bars and extending vertically between the side of said frame and said bars, and means for moving one of said bars toward the other, whereby a U-shaped clip may be disposed between said bars and be clamped therein with said member disposed in the bight of said clip.

3. A holding means for a plurality of brush holding clips comprising an open-work frame adapted to fit in a receptacle, means on said frame engaging said receptacle for holding said frame therein, a bar secured to the bottom of said frame and extending adjacent one side thereof, means movable towards said bar, members spaced along said bar and projecting between said bar and frame, whereby a U-shaped brush holding clip may be disposed between said bar and one of said members with said members disposed in the bight thereof, and be clamped between said bar and member.

4. A holding means for a plurality of brush holding clips comprising an open-work frame adapted to be received in a receptacle and extend around the sides thereof, means for supporting said frame in said receptacle, a member extending across the bottom of said frame adjacent one side thereof for supporting a plurality of U-

shaped brush holding clips, a member extending vertically adapted to be disposed in the bight of a clip, means movable toward said first mentioned member for clamping said clip thereon, and means for moving said spaced members toward the side of said frame for clamping said clip against said side.

5. A holding means for a plurality of brush holding clips comprising a rectangular frame adapted to be received in a receptacle, a bar extending across the bottom of said frame and secured thereto adjacent one side thereof, a bar extending across the 10 top of said frame over said first mentioned bar, a vertically extending member carried by one of said bars and extending between said bars and the side of said frame, means for moving said bars together and means 15 for moving one of said bars toward said side of said frame, whereby a U-shaped clip disposed between said bars and with said member received in the bight thereof may be 20 clamped in said frame.

25 6. A holding means for a plurality of brush holding clips having in combination, a frame adapted to be disposed in a receptacle adjacent the top thereof, means for supporting said frame in said receptacle, a 30 member extending across said frame from one side of said receptacle to the other adjacent one side of said frame and receptacle, a member secured to said last mentioned member and having a portion thereof 35 bent downwardly and disposed between said last mentioned member and one side of said frame and means for moving said members toward said side of said frame whereby a U-shaped clip may be disposed with its bight 40 portion between said last mentioned member and said side of said frame and clamped therebetween.

In testimony whereof I affix my signature.
EINAR PEARSON.
